ROCKING AND SWIVEL TOY

Carl L. Doerr, Long Beach, Calif., assignor to Doerr
Enterprises, Inc., Long Beach, Calif.

Filed Apr. 17, 1962, Ser. No. 69,742

Term of patent 14 years

(Cl. D34—5)

FIG. 1 is a front perspective view of a rocking and swivel toy, showing my new design therefor;

FIG. 2 is a fragmentary, side elevational view thereof; and

FIG. 3 is a fragmentary, rear elevational view thereof.

I claim:

The ornamental design for a rocking and swivel toy, substantially as shown.
